HENRY LOMAX, OF OVER DARWEN, GREAT BRITAIN.

Letters Patent No. 96,017, dated October 19, 1869.

IMPROVEMENT IN FEEDING-MECHANISM FOR SEWING-MACHINES.

The Schedule referred to in these Letters Patent and making part of the same

To all whom it may concern:

Be it known that I, HENRY LOMAX, of Over Darwen, in the county of Lancaster, Kingdom of Great Britain and Ireland, have invented certain new and useful "Improvements in the Construction of Sewing-Machines, or Machines Used for the Sewing of Woolen, Cotton, Silk, or other Fabrics, or in the Making of Garments or Parts of Garments therefrom, or other like work," and I do hereby declare that the following is a full, clear, and exact description of the same, reference being had to the accompanying drawings, and to the letters of reference marked thereon.

This invention relates to an improved construction of those parts of the sewing-machine which press and move the material operated upon by means of what is usually termed a presser-foot.

I employ a presser-foot of a novel and improved construction, consisting of two parts—an outer frame, and an inner foot that presses and moves the material—the whole being constructed and arranged as hereinafter more particularly described, and shown in the annexed drawings.

In order that the nature and object of my invention, and the means of performing it may be distinctly understood, I will now proceed particularly to describe the same, and I have hereunto annexed a sheet of drawings, illustrative thereof, and have marked the same with figures and letters of reference, the same letter referring to the same part in the various views, so as to enable any person acquainted with sewing-machines, of the character hereinafter described, to carry my invention into effect.

Figure 1 is a front elevation.

Figure 2, a side elevation, in which—

A shows an eccentric, the swell *a* of which acts on the arm B, forcing it outward, as the arm is hinged at *d* to the rod, or lever C, the bottom of which forms the outer frame or skeleton-presser D.

The lower end of the arm B is connected, by the link *d'*, to the guide *d''*, in which the lever, or rod E works, the bottom of which forms the inner foot F, which presses and moves the material operated upon.

The arm B, being forced outward by the swell *a*, will raise the rod, or lever C and its foot D clear of the material being operated upon, while the rod, or lever E and guides *d''* are depressed.

The swell *a'*, on the eccentric, acts on the lever G, forcing the same outward, the lower end thereof coming in contact with the end of the set-screw H, on the rod, or lever E, forcing the same outward, and giving the desired traverse to the internal foot for carrying or moving the material onward. The said set-screw also determines the length of stitch.

The swells *a* *a'* having passed, the lever C, on which is the outer frame or skeleton-presser, will instantly fall on the material, holding the same securely for the passage of the needle.

Another revolution of the eccentric will again raise the lever C and the outer frame, or skeleton-presser D.

The lever E, being depressed and forced outward, at the same moment, moves forward the material, which, it will be seen, is thus never left loose on the bed-plate of the machine, because, as one foot or presser is raised, the other is depressed. This prevents "puckering," or uneven work.

At J is shown a spring for returning the lever E, as soon as the swell on the eccentric has passed.

K, fig. 3, is a spiral spring, for raising the internal foot-presser F clear of the material, as soon as its traverse is completed.

L is a spiral spring, for depressing the lever C and its outer frame, or skeleton-presser, as soon as the swell of the eccentric is passed.

The levers E G are jointed or hinged, as shown at M, and are connected with the lever C by means of the link N.

Figure 3 shows, in detail, the levers and pressers.

Figures 4, 5, and 6, are plan views of the under face of the internal and external pressers.

The compound presser, constructed and arranged as above described, may be used with or without an under feed motion.

At Figures 7 and 8 is shown another arrangement of levers for actuating my compound presser.

A' is the eccentric, the swell *a'* on which acts on the arm B', forcing it outward, the projection *b'* acting on the end of the set-screw H'.

The loop through which the set-screw works is connected with the lever C', on which is the outer presser D.

The external foot, in this case, is toothed and empowered for moving forward the material.

The internal presser F', on the lever E', is depressed by means of the motion of the link N', through the action of the lever B', which is hinged thereto, as shown at M'.

K' is a spiral spring for raising the lever E' and presser F'; and L', a spiral spring for depressing the lever. This arrangement is intended to be worked in connection with an under feed.

Motion may be imparted to the eccentric by means of a treadle or driving-band and pulley, actuating the shaft R, on which the eccentric is placed, the latter also giving motion to the needle-bar and needle S. These parts are old and well understood, and I do not lay any claim thereto; but

What I do claim, and believe to be new, is—

1. The combination, with the bars carrying the feet D F, of levers B d^1 , operated by a cam, A, or its equivalent, so that one foot shall be depressed, and the other simultaneously elevated, by the movement of the levers, substantially as set forth.

2. The feet E D, rods C E, and lever G, in combination with the levers B d^1 , cam A, and set-screw H, or their equivalents.

In testimony whereof, I have signed my name to this specification, in the presence of two subscribing witnesses.

Witnesses: HENRY LOMAX.
